UNITED STATES PATENT OFFICE.

OTTO EPPENSTEIN, OF JENA, GERMANY, ASSIGNOR TO THE FIRM OF CARL ZEISS, OF JENA, GERMANY.

COINCIDENCE-TELEMETER.

1,021,306.

Specification of Letters Patent. Patented Mar. 26, 1912.

Application filed November 17, 1911. Serial No. 660,802.

To all whom it may concern:

Be it known that I, OTTO EPPENSTEIN, a citizen of the German Empire, residing at Jena, Germany, have invented a new and 5 useful Coincidence-Telemeter, of which the following is a specification.

The invention relates to unioocular telemeters having a horizontal base-line, a line of coincidence parallel to the latter, a larger, 10 erect and a smaller, inverted single image. Of such telemeters two kinds are known as regards the relative position of the single images. In the one kind the two single images are contiguous to one another only 15 in the line of coincidence: this straight line traverses the whole field of the double image, but not the middle of the same. In the other kind the line of coincidence traverses approximately the middle of the double 20 image field and is completed by a boundary line, which is joined to its extremities, to form a closed figure, the image field of the smaller single image. This image field may be entirely surrounded by that of the larger 25 single image, if the extremities of the line of coincidence lie within the double image field. If they lie in the margin of this field, the larger single image field will be divided by the smaller one into two parts. 30 The smaller single image field is then usually given the form of a band running along the line of coincidence, two sections of the margin of the double image field being used to complete its inclosure. As regards the 35 position of the single images relatively to the instrument, there are also two kinds of such telemeters known. In the first kind, which primarily is intended for so-called terrestrial objects, the smaller, inverted single image lies above the line of coincidence; 40 in the second kind, which is intended for so-called aerial objects, this single image lies below the line of coincidence.

The object of the invention is such a utilization of the rays, which are eliminated by the separating prism and otherwise lost, that the second double image produced by these rays is not only available for being viewed in the same manner as the first 45 double image, otherwise solely used, but that this second double image also has the

properties of this first one, save that the position of its single images relatively to the instrument is suitable for aerial objects, when the first double image serves for measuring terrestrial objects, and vice versa. 55 These demands are complied with according to the invention, by optical means being interposed in the path of the lost rays behind the separating edge, by which means 60 the double image presented directly by these rays is suitably transposed, so as to give to it, on the one hand, the prescribed characteristics and, on the other hand, to lay the second axis of emerging rays parallel to 65 the first. Not counting the ocular lenses, these optical means consist of one or more lenses and of several plane reflecting surfaces or exclusively of such reflecting surfaces. In the place of two independent oculars a single one may serve for alternately 70 viewing the two double images, by being either fixed and combined with a movable reflecting prism or itself movably disposed.

In the annexed drawing: Figure 1 represents a double image field suitable for terrestrial objects, presented by a telemeter constructed according to the invention. Fig. 2 shows a second form of such a double image field. Fig. 3 shows a double image field 80 suitable for aerial objects. Fig. 4 shows a second form of such a double image field. Fig. 5 is a diagram showing the optical parts of a telemeter constructed according to the invention. Fig. 6 is a section along 85 the line 6—6 of Fig. 5. Fig. 7 shows a modification of a portion of the optical system of Fig. 5.

In the double images according to Figs. 1 and 2 the smaller, inverted single image 90 lies above the line of coincidence. In the double images according to Figs. 3 and 4 the smaller single image lies below the line of coincidence. The two double images according to Figs. 1 and 3 appertain to a 95 telemeter having a line of coincidence traversing the whole of the double image field, those according to Figs. 2 and 4 to one having a shortened line of coincidence. In each double image field the image of a terrestrial object *a* and that of an aerial object *b* are each twice drawn, once as *a'* and 100

b^r appertaining to the right-hand telescope and again as *a*¹ and *b*¹ appertaining to the left-hand telescope. Where the object-image is shown in full lines, it appertains to that particular single image, in the field of which it lies. Where it is shown dotted, it appertains to the lost portion of the other single image, and is therefore not visible. The two double images for finding the range 10 of terrestrial objects and of aerial objects, Figs. 1 and 3 and similarly Figs. 2 and 4, are not simultaneously visible in the instrument with the position of the object images as shown, corresponding in either case to 15 the completed finding of the range. On the contrary, the transition between Figs. 1 and 3 and in the same way that between Figs. 2 and 4 necessitates, besides the change of ocular, firstly a setting of the instrument as 20 regards the vertical angle, because the terrestrial object *a* and the aerial object *b* are not at the same angular height, and secondly a manipulation of the measuring device, because the aerial object is at a greater 25 distance than the terrestrial object. It is assumed, that the measuring device is located in the right-hand telescope. By its manipulation in Figs. 1 and 2 the smaller 30 single image and in Figs. 3 and 4 the larger one is displaced along the line of coincidence, as out of the system of ray-pencils of either of the two telescopes the separating prism produces in the one double image field the smaller single image, in the other 35 one the larger single image.

The double images produced by the optical system of Fig. 5 may be those according to Figs. 1 and 3. The objective prism *c* and the objective lens *d* are the same in both 40 telescopes. The measuring device is located in the right-hand telescope and is indicated by a shiftable glass wedge *e*. The separating prism consists of two prisms *f*¹ and *f*², cemented together. Between the two is located the silver separating layer *g*, the form and position of which may be gathered from Fig. 6. The lower margin of this layer is the separating edge. Its position above the middle plane of the telescopes causes the 45 difference in size of the single images. Of the two systems of ray-pencils, which emerge in the direction toward the ocular *h* from the separating prism *f*¹ *f*² and produce the double image shown in Fig. 1, the 50 upper one reflected at the separating layer *g* appertains to the right-hand telescope, the one passing through unreflected below the separating edge to the left-hand telescope. By means of the diverse number and 55 arrangement of the reflecting surfaces, which coact in the left-hand and in the right-hand telescope with the image reversing objective *d*, the above mentioned upper system produces a still inverted single image, whereas the lower system produces a

completely reerected one. The lost rays leave the separating prism *f*¹ *f*² in the direction toward the collective lens *i*. Their lower portion appertains to the right-hand, their upper portion to the left-hand telescope. On account of the absence or presence respectively of reflection at the separating layer, the single image presented directly by the (lower) rays of the right-hand telescope is completely reversed, that presented directly by the (upper) rays of the left-hand telescope shows an interchange of right and left. The so constituted double image is completely reversed by the reversing lens *k*, so that the double image according to Fig. 3 results, the single image of which appertaining to the right-hand telescope is erect and lies at the top, while that appertaining to the left-hand telescope is inverted and lies at the bottom. The reflecting prisms *l*, *m* and *n* do not alter anything in this position of the double image, as they offer an even number of reflections in one and the same plane. When this double image Fig. 3 is to be viewed through the 90 ocular *h*, the reflecting prism *n* must be shifted into the position shown by dotted lines.

In Fig. 7 only a ridge prism *o* is interposed in the path of the lost rays, whereby 95 also the double image according to Fig. 3 is produced. At the same time two oculars *h*¹ and *h*² are provided.

I claim:

1. In a horizontal coincidence-telemeter 100 two objective reflecting systems, two objective lenses, a separating prism system located between the objective lenses, these parts being adapted to produce a double image, the single images of which are of different size and the larger one of which is erect and the smaller one inverted, optical means placed behind the separating edge of the said prism system in the path of the otherwise lost rays and adapted to transpose the double image presented by the said rays, so as to place it parallel to the first one and to arrange its single images, as regards the line of coincidence, in the opposite order to the single images in the first double image, an ocular system adapted for alternately viewing both double images and a measuring device placed on one side of the separating prism system.

2. In a horizontal coincidence-telemeter 120 two objective reflecting systems, two objective lenses, a separating prism system located between the objective lenses, these parts being adapted to produce a double image, the single images of which are of different size and the larger one of which is erect and the smaller one inverted, an optical system placed behind the separating edge of the said prism system in the path of the otherwise lost rays and comprising a re- 125
